(57) **CLAIM**

The ornamental design for a bezel, as shown and described.

DESCRIPTION

FIG. 1 is a perspective view of a bezel in accordance with the design;

FIG. 2 is a front view of the bezel of FIG. 1;

FIG. 3 is a back view of the bezel of FIG. 1;

FIG. 4 is a left view of the bezel of FIG. 1;

FIG. 5 is a right view of the bezel of FIG. 1;

FIG. 6 is a top view of the bezel of FIG. 1; and,

FIG. 7 is a bottom view of the bezel of FIG. 1.

The portions of the bezel shown in broken lines form no part of the claimed design.
